(57) **CLAIM**

The ornamental design for a charging cradle for skincare brush, as shown and described.

DESCRIPTION

FIG. 1 is a front, bottom and side perspective view of a first embodiment of a charging cradle for skincare brush of the present invention showing our new design;

FIG. 2 is a top plan view thereof;

FIG. 3 is a bottom plan view thereof;

FIG. 4 is a side elevation view thereof;

FIG. 5 is a front elevation view thereof;

FIG. 6 is a rear elevation view thereof;

FIG. 7 is a front, bottom and side perspective view of a second embodiment of a charging cradle for skincare brush of the present invention showing our new design;

FIG. 8 is a bottom plan view thereof;

FIG. 9 is a top plan view thereof;

FIG. 10 is a side elevation view thereof;

FIG. 11 is a front elevation view thereof;

FIG. 12 is a rear elevation view thereof;

FIG. 13 is a front, bottom and side perspective view of a third embodiment of a charging cradle for skincare brush of the present invention showing our new design;

FIG. 14 is a bottom plan view thereof;

FIG. 15 is a top plan view thereof;

FIG. 16 is a side elevation view thereof;

FIG. 17 is a front elevation view thereof; and,

FIG. 18 is a rear elevation view thereof.

The broken lines shown herein depict environmental subject matter only and form no part of the claimed design.

1 Claim, 15 Drawing Sheets
